Attorney

UNITED STATES PATENT OFFICE

JAMES F. BUTTERLY, OF COLUMBUS, OHIO

TOBACCO PIPE

Application filed October 25, 1930. Serial No. 491,997.

This invention relates to improvements in tobacco pipes, and an object thereof resides in providing means to prevent clogging or fouling of the tobacco at the bottom of the bowl of the pipe and to thereby enable the latter to draw easily at all times.

In carrying out the invention, there is provided over the bottom proper of the pipe bowl a movable or false bottom on which the tobacco is received and pressed when filling the bowl, the construction and operation of this extra movable bottom being such that it may be forced upwardly as a piston against the tobacco and then downwardly to leave a free air space between the movable bottom and the displaced tobacco, thereby preventing compaction of the tobacco into a substantially wad like form which interferes with the free passage of air and smoke through the pipe. It is found in practice that the air space referred to allows space for the swelling or expansion of the lower layers of the tobacco and in this manner overcomes the objectionable compaction referred to. The construction of the movable bottom is such that the latter may be removed from the pipe for cleaning and other purposes and, moreover the bottom is applicable for ready employment in connection with ordinary tobacco pipes.

Another object of the invention resides in perforating the movable false bottom of the pipe bowl and wherein the bottom is formed with a movable hinge stem, the actuating portion of said stem being received within a recess formed in one of the exterior surfaces of the pipe bowl when the false bottom is normally positioned, the arrangement being such that the stem may be removed from said recess and caused to assume a perpendicular position in registration with the axis of the bowl, whereby the stem may be readily grasped and reciprocated by a simple manual operation to move the false bottom vertically or axially of the bowl.

With these and other objects in view, which will appear as the description proceeds, the invention consists in the novel features of construction, combination of elements and arrangements of parts hereinafter fully de-

scribed and pointed out in the appended claims.

In the drawings:

Fig. 1 is a vertical sectional view taken through a tobacco pipe formed in accordance with the present invention;

Fig. 2 is a bottom plan view thereof;

Fig. 3 is a perspective view of the movable false bottom and its associated operating link; and

Fig. 4 is a transverse sectional view on the line 4—4 of Fig. 1.

In the drawings, wherein for the purposes of illustration, is shown the preferred embodiment of the present invention, the numeral 1 designates generally a tobacco pipe of any well known construction, the same including the usual bowl 2, the stem 3 and a mouth piece 4. In the present instance, the bottom of the bowl 2 is provided with an axially arranged opening adapted for the reception of a slightly tapered sleeve 4' which is securely fitted within said opening against accidental displacement. Arranged to be positioned within the sleeve is a tapered stem 5 and formed with or secured to the upper end of the stem 5 is a movable false bottom 6 of the tobacco bowl. Preferably, the sleeve 4, the stem 5 and the bottom 6 are formed from metal although other suitable materials used in pipe manufacture may be utilized.

The movable bottom 6 is preferably of concavo-convex cross sectional formation and is of slightly smaller diameter than the inner diameter of the pipe bowl. The bottom may be perforated or not, as indicated at 7, and is ordinarily positioned in the lower portion of the bowl, as shown in Fig. 1. Preferably, the lower surface of the bottom 6 is provided with an annular groove indicated at 8 designed for the reception of the upper edge of the sleeve 4 which, in conjunction with the tapered form of the stem 5, provides for a double seat of the opening formed in the bottom of the bowl to prevent undue escape of fluids from the pipe bowl in channels other than that provided by the main passageway 9 of the stem 3. The location of the sleeve 4 is such that when the bottom 6 is normally positioned, the same will be disposed in a plane

slightly above that of the passageway 9 in order that the false bottom will not interfere with the desired passage of smoke through the pipe. I preferably use a ring 10 of an absorbent material such as cotton or fabric below the false bottom and around that portion of the sleeve 4 which projects into the bottom of the bowl, in order that the absorbent material will retain liquids or oils developed by the burning of the tobacco and to prevent the passage of such fuels through the main stem 3 of the pipe.

The lower portion of the stem 5 is pivotally connected as at 11 with an operating link 12. When the pipe is in use, the link 12 occupies a longitudinally extending recess 13 formed in the lower exterior surface of the pipe bowl and the stem 3, in order that the link 12 will lie flush with the exterior surfaces of the pipe and will not in any way interfere with or mar the general configuration thereof. The link is preferably provided at a point midway of its length with a depression 14 which receives a convex enlargement 15 formed in connection with one of the side walls of the recess 13, whereby the link is positively locked or retained in its folded or inactive position in said recess.

In operation, the false bottom 6 is positioned as shown in Fig. 1 and the link 12 is folded to lie within the recess 13. Tobacco is then placed in the bowl of the pipe in the usual manner, as indicated at 16, the tobacco being pressed downwardly within the bowl until it securely engages with the bottom 6. The tobacco is then ignited and the pipe smoked in the usual manner. The smoke may pass through the perforations 7 provided in the false bottom, thence through the ring of absorbent material and finally through the passageway 9 to the mouth of the smoker. If the tobacco has been too firmly tamped into the bowl during the filling operation, this condition may be relieved by rocking the link 12 to the vertical dotted line position disclosed in Fig. 1, and by applying upwardly directed pressure to the link, the false bottom may be raised to move the body of tobacco in the bowl 2 upwardly for a slight distance. The false bottom is then restored to its normal position which results in leaving a slight air space between the upper surfaces of the false bottom and the body of tobacco in the bowl 2. By this operation, the body of tobacco is loosened sufficiently to provide for the free passage of air and smoke therethrough and the air space produced in the base of the bowl also facilitates free drawing. The burning of tobacco frequently generates oils and liquids, and by utilizing the absorbent material 10 around the stem and guarding the entrance to the passageway 9, a convenient means is provided for preventing such liquids from reaching the mouth of the pipe user. This

ring of absorbent material may be replaced from time to time. Thus, by virtue of the construction described, I have provided a pipe capable of producing at all times a cool dry smoke. The false bottom may be operated to remove ash and partially burned tobacco from the bowl in an effective manner so that it is unnecessary to use extraneous scraping and cleaning tools. Due to the construction of the false bottom and the provision of the absorbent ring, it is impossible for slugs or small pieces of tobacco to enter the mouth and this feature is particularly advantageous when dry or small pieces of tobacco are being smoked. As stated, the absorbent material takes up the oil released by the burning of tobacco and by its position in the base of the pipe bowl, the absorbent may be easily removed and other rings substituted from time to time. By reciprocating the false bottom, the tobacco can be positively ejected from the bowl avoiding completely the digging and scraping operations heretofore involved in the removal of ash and charged tobacco from pipe bowls.

The link 12 is of such diameter that it passes freely through the sleeve 4 so that the entire false bottom together with its pivot link may be removed from the pipe through the open upper end of the bowl. Preferably, the link 12 is of such length with respect to the height of the bowl that in replacing the false bottom with the link 12 hanging perpendicular thereto, the extreme lower end of said link may then be manually guided into the enlarged upper end of the sleeve 4 so that by releasing the false bottom or disk 6, the latter will drop into the bottom of the bowl and the link 12 will project below the bottom of the bowl as shown by dotted lines in Fig. 1. Then by oscillating the link around the pivot 11, it may be restored to its inactive position within the recess 13 and positively locked therein. I am aware of the fact that it has been proposed heretofore to provide tobacco pipes with movable false bottoms, disks or plates but so far as I know, none of these earlier constructions is provisioned for completely removing through the open upper end of the pipe bowl, the ejector means as herein disclosed.

The construction of my pipe is essentially simple and does not involve any change in standard pipe design. In fact, the construction may be embodied in any of the standard forms of tobacco pipes now in general use.

While I have described the construction comprising the preferred form of my invention in considerable detail, it will be understood however that variations may be made herein without necessarily departing from the scope and spirit of the invention as the latter has been defined in the following claims.

What is claimed is:

1. In a tobacco pipe, a tobacco receiving bowl having a smoke outlet in the bottom thereof, a tapered sleeve stationarily positioned in an opening formed axially in the lower wall of said bowl, the upper end of said sleeve terminating above the bottom surface of the bowl, a perforated bottom member slidably mounted in said bowl, a stem formed with said bottom member and normally received within said sleeve, said bottom being adapted to engage with the upper end of said sleeve whereby to maintain said member in spaced relation from the bottom of said bowl and the smoke outlet leading therefrom, and a link pivotally connected with the lower end of said sleeve and normally adapted to occupy a longitudinally extending recess formed in one of the exterior surfaces of the bowl, said link being so proportioned as to pass freely through said sleeve when in vertical alignment therewith.

2. In a tobacco pipe, a bowl formed with a tobacco receiving chamber having a smoke outlet in the lower portion thereof, said bowl being further formed with an axial opening in the bottom of said chamber, a sleeve positioned in said latter opening and having the upper end thereof terminated within said chamber above the bottom of the latter, a perforated disk movable up and down in said chamber and having an annular groove formed in its upper surface arranged to receive the upper edge of said sleeve when the disk is positioned on the sleeve, the portion of the sleeve projecting upwardly into said chamber constituting a centering stud for the reception of a removable ring of an absorbent material, a stem formed with said disk and receivable within said sleeve, and a link pivoted at one end to said stem and said link being proportioned for free passage through said sleeve, said link when inactively positioned being disposed within a longitudinally extending recess provided in the lower exterior surface of said bowl.

In testimony whereof I affix my signature.
JAMES F. BUTTERLY.
